SWITCH CONTROL MECHANISM

Martin Luther Klingler, Hershey, Pa., assignor to AMP
 Incorporated, Harrisburg, Pa.
 Filed May 11, 1966, Ser. No. 549,335
 7 Claims. (Cl. 74—122)

This invention relates to a switch control mechanism for electrically driven tools or presses of the type in which an electric motor is utilized to oscillate a pair of circular ratchets or clutches in out-of-phase relationship.

The copending application of Martin L. Klingler, Ser. No. 380,398, filed July 2, 1964, now abandoned, discloses and claims an electrically operated tool comprising a pair of circular ratchets or clutches in side-by-side relationship. The outer races of these clutches have radially extending arms on which followers or rollers are mounted, these rollers being engaged by a swash plate to cause out-of-phase oscillation of the outer races. The inner races are thus rotated about a common axis in stepwise fashion at a speed which is substantially less than the speed of rotation of the swash plate. A pin or the like is eccentrically mounted in this axis and revolves thereabout when the inner races are rotated. A motion transmitting means is utilized to translate the movement of this pin along a circular path to rectilinear movement of a reciprocal ram or the like. A similar tool is disclosed and claimed in application Ser. No. 549,292, filed May 11, 1966, by Martin Luther Klingler, this application being a continuation-in-part of application Ser. No. 380,398.

Tools and presses of the type disclosed in the above-identified Klingler applications will often have a relatively small high-speed motor with a relatively slow moving pin to drive the reciprocal ram. Such tools are thus capable of utilizing a small high-speed motor to develop a relatively high compressing force for crimping terminals or performing similar operations. It is desirable to provide a means to bring the motor up to its operating speed before imposing the load, in other words, before engaging the rollers with the rotating swash plate which is driven by the motor. The present invention is generally directed to the provision of an improved control mechanism which accomplishes this result of permitting the motor to attain its operating speed before imposition of the load.

The objects of the invention are achieved in one preferred embodiment in which the motor is energized by a switch and the rollers or followers on the outer races of the clutches are biased against the swash plate by a spring or other suitable resilient means. A trigger or starter button is arranged such that when it is pressed or squeezed, the switch is first closed to start the motor and permit it to attain its operating speed. Further squeezing of the trigger or depression of the button has the effect of stretching or elongating the springs which bias the rollers against the swash plate. When these springs are stretched and the rollers are pulled against the swash plate, the outer races are oscillated as explained above and the drive pin commences its movement along a circular path around the axis of rotation of the inner races.

In the drawing:

FIGURE 1 is a side view with parts broken away of a preferred form of electrically driven hand tool incorporating a starting mechanism in accordance with the invention;

FIGURE 2 is a perspective view of the starting mechanism; and

FIGURE 3 is a view taken along the lines 3—3 of FIGURE 1.

In the description which follows, the structural features of the tool are described only to the extent necessary for an understanding of the present invention which relates to

2

the starting mechanism. Reference is made to the above-identified application Ser. No. 380,398 and Ser. No. 549,292 for a more complete description of the structural features of the tool.

5 A tool 2 in accordance with the general teachings of application Ser. No. 380,398 comprises a handle 4, spaced apart frame plates (one of which is shown at 10) and a motor 6 horizontally mounted on the upper side of the handle. A swash plate 8 is mounted on the end of the shaft of the motor for engagement with rollers 26 described below. A C-shaped head 12 is mounted between the frame plates 10 in any suitable manner, for example, in the manner shown in application Ser. No. 532,393, filed Mar. 7, 1966, by Martin Luther Klingler, and a fixed crimping anvil is mounted against one arm of this head. A movable crimping die 16 is mounted on the end of a reciprocable ram 18 for cooperation with the anvil to crimp electrical terminals during the operating cycle as described below. The ram 18 is guided in suitable guide ways contained in the head for movement towards and away from the anvil.

20 The driving mechanism for the ram comprises a pair of circular ratchets or clutches having circular elements or outer races 20 from which extend radial arms 24. The rollers 26 are mounted on the ends of these arms adjacent to the swash plate 8 so that these outer races will be oscillated in out-of-phase relationship during rotation of the motor shaft. The outer races are mounted on a common inner race 28, spring biased detents 29 being effective between the outer races and the inner race to cause the inner race to be rotated stepwise about the common axis of the two clutches when the outer races are oscillated by the swash plate. Drive pins 30 extend from the sides of the inner race and are eccentrically disposed with respect thereto. These drive pins are connected by links 32 to a common pivot pin 34 forming the knee of a toggle mechanism 36, 38. The link 36 of this toggle is pivoted between the frame plates at 37 while the links 38 are pivotally connected to the end of the ram 18. It will thus be apparent that during movement of the pins 30 along a circular path, the toggle will be straightened and later broken to drive the die 16 towards and away from the anvil 14.

25 The thrust developed by the ram to crimp a terminal (or perform any similar operation) may be quite high and the motor 6 should be of the smallest size possible to preserve the portability and compactness of the tool. Ordinarily, this motor will be a relatively high-speed low torque motor and the motion translating mechanism comprising the clutches and the toggle is effective to utilize its developed power for the crimping operation which requires a high force. The motor should be permitted to attain its full operating speed before a load is imposed, a result which is achieved by the starting and trigger mechanism of FIGURE 2 which will now be described.

30 The motor is energized by a small switch 40 contained in the handle and including a switch button 42. This button can be depressed to close the switch by a spring arm 44 mounted on the switch housing and extending generally upwardly in FIGURE 1. The trigger of the disclosed embodiment 46 is generally channel-shaped and is pivotally mounted on its upper end on a pin 48 extending between the side plates. Advantageously, a plastic cover or shield 50 is mounted on the trigger to increase operator comfort and convenience. A pin 52 extends between the sides of the trigger at its lower end and a rod 54 has its one end hooked over this pin as shown in 56. This rod extends rearwardly through an opening in the upper end of the spring arm 44 and has a collar 58 mounted thereon intermediate its ends. A coil spring 61 is interposed between this collar and this spring arm 44 so that if the trigger is swung in a counterclockwise direction

from the position of FIGURE 1, the spring arm 44 will be flexed rightwardly to close the button 42. The rod can move further rightwardly after this button is closed as will be explained below during engagement of the followers 26 with the swash plate.

A channel-shaped plate 60 is mounted in the upper portion in the handle of the frame plate 10 on a pivot pin 64. A pair of springs 66, 68 are hooked to the rearward or right-hand end of this plate and extend upwardly and are hooked to ears integral with and extending from the outer races 20 of the two clutches. When the parts are in their normal positions, the rollers 26 will be biased against the surface of the swash plate but will not be held against this surface with sufficient force to cause movement of the inner races of the clutches. If, however, the plate is swung in a clockwise direction of its position of FIGURE 1, the outer races will be pulled relatively downwardly and the followers will be held against the surface of the swash plate with a degree of force such that the inner race of the clutches will be moved or rotated about the common axis of the two clutches.

At its forward end, the plate 60 is provided with a pair of elongated slots 72 in its sides through which a pin 74 extends. A link 76 is mounted on this pin 72 at one end and is mounted on the pin 52 in the trigger at its other end. The link extends generally diagonally with respect to the plate 60 so that depression of the trigger will cause the plate 60 to swing in a clockwise direction with respect to the pin 64.

In use, the operator will merely squeeze the trigger to energize the motor and to engage the rollers 26 of the clutches with the swash plate. However, this action takes place in two distinct steps. During the first step, and during initial rightward movement or counterclockwise movement of the trigger, the rod 54 is moved rightwardly flexing the spring 44 and closing the switch button 42. Very little movement is required to close this switch button since the switch is quite small. During this portion of the cycle, the pin 74 moves relatively rightwardly to the limit of its permitted travel in the slots 72 and the plate 60 thus remains stationary. During this brief interval, the motor is energized but is not loaded so that it is permitted to attain its maximum or operating speed. In the second stage of the starting operation, continued squeezing of the trigger results in clockwise movement of the plate 60 with respect to the pivotal axis 64 and the springs 66, 68 are pulled downwardly from the position of FIGURE 1. These springs, in turn, bias the outer races relatively downwardly and the rollers are held against the face of the swash plate with a degree of firmness such that the inner races are moved stepwise about the common axis. So long as the trigger is held in its fully depressed condition, the pins 30 will continue to move in a circular path and the ram 18 will be reciprocated. It will be apparent that the springs 66, 68 will be stretched slightly during oscillation of the outer races and will be always biased against the surface of the swash plate.

The overall advantage of the starting and trigger mechanism described above is that a small high-speed motor 6 can be used in the tool although a relatively high thrust or force is developed in the ram for the reason that the load is not imposed on the motor until it attains its operating speed. An additional advantage is that the crimping operation can be stopped if desired at any time by merely releasing the trigger and can be started again by again squeezing the trigger. This feature is desirable in the crimping of certain types of terminals in that the terminal can be manually held between the die and anvil and the trigger squeezed until the die moves rightwardly to the point where it lightly holds the terminal against the anvil. The operator then has a free hand (since he need not hold the terminal) and can insert the wire into the terminal barrel for the crimping operation. Changes in construction will occur to those skilled in the

art and various apparently different modifications and embodiments may be made without departing from the scope of the invention. The matter set forth in the foregoing description and accompanying drawings is offered by way of illustration only. The actual scope of the invention is intended to be defined in the following claims when viewed in their proper perspective against the prior art.

I claim:

- 10 1. In a motion transmitting means comprising a pair of circular ratchets in side-by-side relationship on a common axis, each ratchet comprising first and second circular elements, each ratchet having means effective between its first and second element permitting said first element to rotate around said axis in either direction and permitting said second elements to rotate in unison in only one direction with either of said first elements while preventing rotation of said second elements in the opposite direction, camming means for oscillating said first elements in out-of-phase relationship, engaging means for engaging said camming means with said first elements, electric motor means for actuating said camming means, switch means for said motor means, and starting means effective to initially close said switch means and subsequently actuate said engaging means whereby, during starting, said motor means is permitted to attain its operating speed before engagement of said first elements with said camming means.
- 15 2. In a motion transmitting means comprising a pair of circular ratchets in side-by-side relationship on a common axis, each ratchet comprising inner race means and outer race means, said inner race means of said ratchets being rotatable in unison and said outer race means being oscillatable independently, camming means for oscillating said outer race means in out-of-phase relationship, engaging means for engaging said outer race means with said camming means, electric motor means for actuating said camming means, switch means for said motor means, and starting means effective to initially close said switch means and subsequently actuate said engaging means whereby during starting, said motor means is permitted to attain its operating speed before engagement of said outer race means and said camming means.
- 20 3. A device as set forth in claim 2 wherein said camming means comprises a swash plate, said outer race means having follower means for engagement with said swash plate, said engaging means comprising resilient means for biasing said follower means into engagement with said swash plate.
- 25 4. A device as set forth in claim 2 wherein said starting means comprises trigger means concatenated with said switch means and said engaging means and effective, upon squeezing thereof, to first close said switch means and subsequently actuate said engaging means.
- 30 5. A device as set forth in claim 4 wherein said engaging means comprises resilient means for biasing said follower means into engagement with said switch means.
- 35 6. In a motion transmitting means comprising, a pair of clutches in side-by-side relationship, each of said clutches comprising first and second circular elements, said elements being disposed on a common axis, each clutch having means effective between its first and second element permitting said first element to rotate around said axis in either direction and permitting said second element to rotate in only one direction with said first element while preventing rotation of said second element in the opposite direction, a swash plate mounted for rotation on an axis extending transversely of said common axis, follower means on each of said first elements normally disposed adjacent to, and engageable with, said swash plate, a motor for rotating said swash plate, switch means for energizing said motor, resilient means for moving each of said first elements through a minor arc in said opposite direction and against said swash plate, and trigger means
- 40
- 45
- 50
- 55
- 60
- 65
- 70
- 75

concatenated with said switch means and resilient means and effective, upon squeezing thereof, to first close said switch means and energize said motor and to subsequently actuate said resilient means to move said follower means against said swash plate whereby, said motor is first started and reaches an operating speed and said followers are engaged with said swash plate when said swash plate is rotating, and said first elements are oscillated by said swash plate and said second elements are rotated in said one direction.

7. A device as set forth in claim 6 wherein said second elements of said clutch means are integral with each other.
